UNITED STATES PATENT OFFICE

GEORGE E. HULSE, OF NEW HAVEN, CONNECTICUT, ASSIGNEE TO THE SAFETY CAR HEATING & LIGHTING COMPANY, A CORPORATION OF NEW JERSEY

REFRIGERATION

Application filed December 3, 1930. Serial No. 499,869.

This invention relates to refrigeration.

One of the objects of this invention is to provide a refrigeration system which will be highly efficient in operation while reliably coping with certain variable conditions met with in practice. Another object of this invention is to provide a system of the above character which will be of thoroughly simple and practical arrangement and of dependable and lasting action. Another object is to provide a device of the above character which, because of such features as thorough simplicity of its working parts, will require a minimum amount of attention and may be operated by unskilled attendants. Another object is to provide a system of the above character which will be economical in use. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings in which is shown one of various possible embodiments of my invention,

Figure 1 is a transverse cross sectional view of a railway refrigerator car showing certain parts of my apparatus and system in end elevation,

Figure 2 is a central cross sectional view of a valve used in my system,

Figure 3 is a front elevation of a valve, partially in cross section, employed in my refrigeration system, and

Figure 4 is a longitudinal cross sectional view taken along the line 4—4 of Figure 1 showing certain parts in side elevation.

Similar reference characters refer to similar parts throughout the several views of the drawings.

Considering first certain of the mechanical features of this invention and referring first to Figures 1 and 4, there is generally indicated at 10 a railroad refrigerator car which may be of any suitable construction; one of its ends, however, is closed off by a wall 11

of heat-resistant material to form a compartment 12. The exterior walls 13 of car 10 are also constructed in any suitable manner to be of low heat conductivity. Thus compartment 12 is well insulated from the temperature of the exterior and also from the storage space or chamber 14 of the car whose temperature is to be regulated.

Within compartment 12 and preferably disposed to one side thereof is a small compartment 15 insulated from compartment 12 by walls 16 and an internal combustion engine 17 is housed therein. Thus the heat ensuing from the operation of this engine is excluded from compartments 12 and 14. This engine may be of any desired construction although it has been found preferable to employ a small Diesel engine adapted to run continuously for substantial periods of time. Engine 17 may be cooled in any suitable way; for example, an opening 18, leading to the exterior of the car, is disposed adjacent a fly wheel 19 of the engine and another opening 20 is positioned in the upper portion of the compartment. A fan 21 secured to or built into fly wheel 19 draws air in through opening 18 and forces it out through opening 20 after passage over the engine. This circulation of air cools the engine to an efficient working temperature, and also decreases the possibility of sufficient heat being retained in compartment 15 to cause leakage through walls 16 into compartments 12 and 14.

Crankshaft 22 of engine 17 extends through wall 16 to drive a shaft 23 from which, by way of suitable gearing 30, is driven a compressor 24. Compressor 24 is preferably of the rotary type and provided with an inlet pipe 25 and an outlet pipe 26.

Outlet pipe 26 leads to the top 27 of a plurality of tubes 28 which form any suitable efficient air-cooled condenser. Condenser 28 is adapted to receive a compressed gaseous refrigerant, such as sulphur dioxide, from compressor 24, through outlet pipe 26 and to reduce it in temperature, thereby condensing and changing it to liquid form. As is more clearly shown in Figure 4, condenser 28 is positioned adjacent an opening 31 leading to

the exterior of the car 10. This opening is provided with a sheet metal grating generally indicated at 32, thus permitting outside air to enter and pass over condenser 30.

- 5 A conduit 33, for example of sheet metal, has its upper portion fitted about opening 31 and extends downwardly toward the floor of car 10 to enclose condenser 28, compressor 24, and the various working parts thereof.
- 10 An opening 34 extends through the floor of car 10, and the opposite end of conduit 33 is terminated at this opening. By this construction air entering through opening 31 flows down over condenser 30 and compressor
- 15 24 to exit through opening 34.

- To insure this movement, a fan 35 is mounted on a shaft 51 connected to driving shaft 23 by a coupling 36 and rotatably held in place by a standard 37. This fan, when actuated, forces air inwardly through opening 31, causing the above described movement of air to take place, extracting heat from the condenser 28 and compressor 24 within conduit 33, the heated air passing out through opening 34.

The liquefied refrigerant is passed by a pipe 38 (Figure 4) to a receiver 39 to be stored for later refrigerating purposes. A reservoir 40 at the top of the car in the drawings is insulated by walls 41 from compartments 12 and 14 and holds a substantial quantity of liquid, such as brine, to be circulated in space 14 and absorb heat therefrom by means to be described hereinafter. Disposed within reservoir 40 is an expansion coil 42 connected to receiver 39 by pipe 43 in which is inserted an expansion valve 44 controlled by the pressure in evaporator coil 42. After expansion and evaporation in coil 42, the refrigerant leaves coil 42 by a pipe 46, but under the control of a thermostatic valve 45, and then passes to the inlet pipe 25 of compressor 24. Valve 45 is thermostatically controlled in accordance with the temperature of the contents of reservoir 40 and, as is now clear, is on the suction side of compressor 24. When the brine in tank 40 has been sufficiently cooled, valve 45 closes, stopping the cycle of steps through which the refrigerant passes to achieve refrigeration. Upon increase in temperature of the brine, valve 45 opens, whence evaporation of liquefied refrigerant in coil 42 may proceed and the cycle is resumed. Valve 44 thus allows liquefied refrigerant, under pressure in receiver 39 and condenser 28, to expand into expansion coil 42 where it evaporates to maintain at relatively fixed low temperature under control of valve 45, the contents of reservoir 40, and is then led back to the compressor 24 to repeat the refrigeration cycle.

A pipe 47 leads from the bottom of reservoir 40 and is connected to a series of pipes generally indicated at 48 in space 14. Lead-

ing from the other end of pipes 48 is a pipe 49 extending through partition 11 to enter compartment 12.

Anchored to the floor of car 10 is a rotary pump 50, driven by shaft 51, which is connected to driving shaft 23. The inlet 52 of pump 50 is connected to pipe 49 and the outlet 53 is connected to a pipe 54 leading to the top of reservoir 40. When pump 50 is actuated by shaft 51, a circulation of the brine takes place through pipes 48, reservoir 40 and connected parts, as indicated by the arrows in the drawings. Thus the brine, cooled by coil 42, leaves reservoir 40, passes through pipes 48, extracting heat from chamber 14, and, warmed, enters pipe 49 to pump 50 and leaves pump 50 to re-enter reservoir 40 by pipe 54, to be cooled again by coil 42.

Inlet pipe 49 of pump 50 and outlet pipe 54 are connected by pipe 55 and pipe 56 respectively, to form a bypass generally indicated at 82, and interposed between pipes 55 and 56 is a thermostatic valve 57 whose construction is to be described hereinafter. A thermostatic bulb 58 is disposed in space 14 and is connected by pipe 59 to valve 57 to make the latter responsive, in a manner to be hereinafter more clearly described, to the temperature of space 14. Likewise, a thermostatic bulb 60 is disposed in reservoir 40 and is connected to thermostatic valve 45 by a pipe 61 to make the valve 45 responsive to the temperature of the medium contained in this reservoir.

Referring now more particularly to Figure 2, a possible construction of thermostatic valve 45 is shown in detail. A bellows 62 is anchored as at 63 to a casing 64. Pipe 61 leading from thermostatic bulb 60 is threaded into an inlet 65 in this casing to be connected directly to bellows 62. A casing 66 is secured to annular flanges 67 extending from casing 64 by any desired means, such as screws 68. A partition 69 separates the interior of casing 64 from the interior of casing 66. Casing 66 is divided into two chamber portions 71 and 73 by a valve seat 70, portion 71 being connected at port 72 to pipe 46 leading from coil 42, and portion 73 being connected at port 73 to pipe 46 leading to compressor 24. Thus the evaporated refrigerant, in passing from evaporator 42 to compressor 24, must pass through valve opening 75 in the seat 70.

A rod 76, secured to the unanchored end of bellows 62, extends through a suitable stuffing box in wall 69 and has connected at its opposite end a valve 77 coating with and controlling valve opening 75. Bulb 60, submerged in the brine in reservoir 40, contains a suitable volatile liquid sensitive to temperature changes. When an increase in temperature of the brine, and hence of the volatile liquid in bulb 60, takes place, the vapor pressure increases and the resultant increase

in pressure in the bellows 63 causes the unanchored end of the bellows to force shaft 76 to the left, as viewed in Figure 2, to open valve 77 and thus permit the passage of evaporated refrigerant from coil 42 to condenser 24. Reduction in temperature of the brine to the desired value causes a reverse action and the closure of valve 75-77.

Referring now to Figure 3, there is shown 10 a possible construction for valve 57. Preferably it is substantially similar in construction to valve 45 of Figure 2. A port 78 of the valve is connected to pipe 56 of the bypass 82, and the other port 79 is connected to pipe 15 55 of bypass 82. A valve head 80, coacting with valve opening 81, is controlled by a thermostatic bellows 83 connected to thermostatic bulb 58 (Figures 1 and 4) by pipe 20 59, bulb 58 containing a suitable volatile liquid whose action, in response to the temperature in space 14, will now be clear in view of the above described control of valve 45.

Considering now the action of my refrigeration system, let it be assumed that the 25 refrigerating car is in transit and is loaded with perishable goods which should be maintained between certain definite temperature limits for most efficient carriage and storage. Reservoir 40, pipes 48, and associated pipe 30 connections are filled with brine of suitable composition, and engine 17, which, as above noted, is adapted to run continuously for substantial periods of time, is in operation. Furthermore, let it be assumed that the car 35 has just been loaded and the engine 17 just started; therefore the temperature in space 14 is above that preferred and the temperature of the brine in reservoir 40 is above that preferred for proper refrigerating purposes. 40 This brine should be maintained at a temperature substantially below that of the temperature at which space 14 is to be maintained. For example, if space 14 in the car is to be maintained at 40° F., it may be desirable 45 to maintain the brine at a temperature of 35° F.

As the engine 17 is running at its normal speed of operation, compressor 24, which is connected directly thereto, compresses the 50 gaseous refrigerant and forces it through outlet pipe 24. The compressed gaseous refrigerant enters condenser 28 to be cooled, condensed, and thus liquefied. Fan 35 is running. Thus a constant flow of air is moving down over condenser 28, compressor 24 and out through opening 34. This combined compressing and cooling effect liquefies the gaseous refrigerant and the refrigerant is then conducted to receiver 39 by pipe 38.

60 As the temperature of the brine in the reservoir 40 has been assumed to be above 35°, the substance contained in thermostatic bulb 60 is at a vapor pressure sufficient to actuate valve 45, the pressure causing the unanchored end of bellows 62 to move valve head 75

away from its seat 70, thus allowing free passage of evaporated refrigerant from evaporator 42 through the valve to the compressor 24. As the action of the condenser and compressor continues, liquefied refrigerant flows from receiver 39, through pipe 43, under control of expansion valve 44, to expansion coil 42. The liquefied refrigerant evaporates in coils 42 to absorb heat from the brine contained in reservoir 40. The evaporated refrigerant returns to compressor 24 by pipe 46 (valve 45 being open) connected to inlet pipe 25 to repeat the refrigeration cycle. This action continues until the brine is cooled to the desired temperature, above assumed to be 35°, when the vapor pressure in thermostatic bulb 60 becomes reduced to cause bellows 62 to contract and reseat valve head 75, thus closing valve 45 and stopping the flow of gaseous refrigerant to compressor 24. Cooling of the brine ceases for no expansion is taking place in coil 42 until the temperature of the brine rises above 35°, when this action is repeated.

Simultaneously with the above described 90 action, rotary pump 50 is being actuated by driving shaft 51 to circulate the brine through the circulating path which includes pipes 48 in space 14. The cooled brine leaves the bottom of reservoir 40 through pipe 47 95 to enter pipes 48 and extract heat from space 14. After exerting this cooling effect on space 14, the warmed brine travels through pipe 49, to pump 50 and through pipe 54 back to the top of reservoir 40 where it is cooled 100 by the action of expansion coil 42. During this action, valve 57 is closed. This circulation of brine continues until the temperature in space 14 reaches that preferred, above assumed to be 40° F., when the vapor pressure in thermostatic bulb 58 is reduced to cause bellows 57 to contract, unseating valve head 80 from its seat 81, and thus opening valve 57. Bypass 82 is thus made effective 105 as a shunt. The opening of valve 57 forces the brine to flow from outlet 53 of pump 50 through pipe 56, valve 57 and pipe 55 and back to the inlet of the pump. Bypass 82 is thereby established and pump 50 has no effect 110 on the brine in reservoir 40 or in pipes 48. Circulation of the brine in space 14 ceases until the temperature of this space rises above 40° when the valve 57 closes, bypass 82 is made ineffective, and the circulation of brine through its heat-absorbing path is 115 resumed.

The compressor 24 is being driven continuously so that the brine may be maintained at an even temperature subject to the control of thermostatic valve 45. Thus any rise in the temperature of the brine in reservoir 40, due, for example, to the return thereto of warmed brine from pipes 48, opens valve 45 to cause refrigeration to take place in reservoir 40. The latter may, and preferably 120

does, have a substantial capacity so as to hold, for circulation as needed, a substantial quantity of brine, the latter being cooled, by coil 42, as and when cooling thereof is needed.

5 In this manner a practical method for maintaining the goods in space 14 at a substantially constant temperature is assured.

It will thus be seen that by this thoroughly simple and practical construction and apparatus I have provided a refrigeration system well adapted to withstand the hard wear and tear of operation on vehicles such as railroad cars. By employing a brine circulating system operating independently of the other parts of my refrigerator system, I am able to maintain the refrigerated space of the vehicle at a temperature whose variations will be slight and inconsiderable. Thus, the perishable goods to be stored will be free from damage due to a quick rise of temperature. The extreme simplicity of the action of the working parts is desirable in that it reduces to a minimum the possibility of a breakdown, and also permits the operation of this apparatus by careless and unskilled attendants. These and many other important advantages and the objects above noted will thus be seen to be successfully achieved.

30 As many possible embodiments may be made of the above invention and as many changes may be made in the embodiment above set forth, it is to be understood that all matter hereinabove set forth, or shown in the accompanying drawings is to be interpreted as illustrative, and not in a limiting sense.

I claim:

1. In a refrigeration system, in combination, means forming a space whose temperature is to be regulated, means for circulating a fluid medium in said space, a reservoir for storing said fluid medium, a refrigeration unit employing a gaseous refrigerant and having an expansion member disposed in said reservoir in thermal contact with said fluid medium, an internal combustion engine adapted to run continuously for substantial periods of time for driving the compressor of said unit, a valve for controlling the flow of said refrigerant to said expansion member, thermostatic means responsive to the temperature of said fluid medium for controlling said valve, a pump for forcing said fluid medium through said circulating means, a by-pass associated with said circulating means, a valve for regulating the effectivity of said by-pass, and thermostatic means responsive to the temperature in said space for controlling said valve.

60 2. In a refrigeration system, in combination, means forming a space whose temperature is to be regulated, a containing means for storing a fluid medium, means for circulating said fluid medium in said space, a refrigeration unit having an expansion mem-

ber disposed in thermal contact with said fluid medium, an internal combustion engine adapted to run continuously for substantial periods of time for driving the compressor of said unit, means for controlling the supply of refrigerant to said expansion member, means responsive to the temperature of said fluid medium for controlling said last mentioned means, a pump for forcing said brine through said circulating means, a by-pass associated with said circulating means, means for controlling the effectivity of said by-pass, and thermostatic means responsive to the temperature in said space for controlling said last mentioned means.

3. In a refrigeration system, in combination, means forming a space whose temperature is to be regulated, a reservoir for storing brine, a circulating system for said brine in said space, a refrigeration unit having an evaporator member for cooling said brine in accordance with the rate of evaporation taking place therein, an internal combustion engine adapted to run continuously for substantial periods of time to drive the compressor of said unit, means for controlling the rate of evaporation in said evaporator member, means responsive to the temperature of said brine for controlling said last mentioned means, means in said circulating system for causing circulation of brine to take place therein, a by-pass associated with said circulating system, means for controlling the effectivity of said by-pass, and means responsive to the temperature in said space for controlling said last mentioned means.

4. In a refrigeration system, in combination, means forming a space whose temperature is to be regulated, a refrigeration unit employing a gaseous refrigerant, an expansion member of said unit thermally related to a fluid and adapted to extract heat therefrom according to the rate of expansion of said refrigerant taking place therein, means responsive to the temperature of said fluid for regulating said rate of expansion, means for circulating said fluid in said space adapted to bring said fluid into thermal relation to said space to extract heat therefrom, a second circulating means for circulating said fluid substantially out of thermal relation with said space, means for causing said medium to flow through either of said last mentioned means, and temperature-responsive means in said space for controlling the action of said last mentioned means.

5. In a refrigeration system, in combination, means forming a space whose temperature is to be regulated, a refrigeration unit, the expansion member of said unit thermally related to a fluid and adapted to extract heat therefrom according to the rate of expansion taking place therein, means responsive to the temperature of said fluid for regulating said rate of expansion, circulating means for said

fluid in said space adapted to bring said medium in thermal contact with said space to extract heat therefrom, a second circulating means for circulating said fluid substantially out of thermal contact with said space, temperature-responsive means in said space for selectively disposing said fluid in either of said circulating means.

6. In a refrigeration system, in combination, means forming a space whose temperature is to be regulated, a refrigeration unit, an expansion member of said unit disposed in thermal contact with a fluid and adapted to extract heat therefrom according to the rate of expansion taking place therein, means responsive to the temperature of said medium for regulating said rate of expansion, circulating means for said fluid in said space adapted to bring said fluid in thermal contact with said space to extract heat therefrom, a second circulating means for said fluid substantially out of thermal contact with said space, means for forcing said fluid through either of said systems, thermostatic means in said space for selectively disposing said medium in either of said two circulating means.

7. In a refrigeration system, in combination, means forming a space whose temperature is to be regulated, a refrigeration unit, motive means for said refrigeration unit, an expansion member of said unit disposed in thermal contact with a fluid and adapted to extract heat therefrom according to the rate of expansion taking place therein, means responsive to the temperature of said medium for regulating said rate of expansion, a circulating means for said fluid adapted to bring said fluid in contact with said space to extract heat therefrom, a second circulating means for circulating said fluid substantially out of thermal contact with said space, means for causing said medium to flow through either of said two circulating means, and temperature-responsive means in said space for regulating the action of said last-mentioned means.

8. In a refrigeration system, in combination, means forming a space whose temperature is to be regulated, a refrigeration unit, motive means for said refrigeration unit, an expansion member of said unit disposed in thermal contact with a fluid adapted to extract heat therefrom according to the rate of expansion taking place in said member, means responsive to the temperature of said medium for controlling said rate of expansion in said expansion member, a circulating system for said fluid adapted to bring said fluid into thermal contact with said space to extract heat therefrom, a second system for circulating said fluid substantially out of thermal contact with said space, a pump for forcing said fluid through either of said cir-

culating means, and thermostatic means in said space for selectively disposing said medium in either of said systems.

9. In a refrigeration system, in combination, means forming a space whose temperature is to be regulated, a refrigeration unit, an internal combustion engine adapted to run continuously for substantial periods of time to drive an element of said unit, an expansion member in said unit disposed in thermal contact with a fluid adapted to extract heat therefrom according to the rate of expansion taking place therein, means responsive to the temperature of said medium for controlling said rate of expansion, circulating means for said fluid adapted to bring said fluid into thermal contact with said space to extract heat therefrom, a second circulating means for disposing said fluid substantially out of thermal contact with said space, temperature-responsive means in said space for selectively disposing said fluid in either of said circulating means.

10. In a refrigeration system, in combination, means forming a space whose temperature is to be regulated, a refrigeration unit for cooling a fluid medium, circulating means for said fluid adapted to bring said fluid into thermal relation with said space to extract heat therefrom, a second system for circulating said fluid substantially out of thermal contact with said space, and means responsive to the temperature in said space for selectively disposing said fluid in either of said two circulating means.

11. In a refrigeration system, in combination, means forming a space whose temperature is to be regulated, a refrigeration unit adapted to cool a fluid upon actuation, motive means for driving an element of said unit, circulating means for said fluid adapted to bring said fluid into thermal contact with said space to extract heat therefrom, a second circulating means for said fluid substantially out of thermal contact with said space, and means responsive to the temperature in said space for selectively disposing said fluid in either of said two circulating means.

12. In a refrigeration system, in combination, means forming a space whose temperature is to be regulated, a refrigeration unit adapted to cool a fluid upon actuation, motive means for driving an element of said unit, a circulating system for said fluid adapted to bring said fluid in contact with said space to extract heat therefrom, a second circulating means for said fluid substantially out of thermal contact with said space, means for forcing said medium through either of said systems, and means responsive to the temperature of said space for disposing said fluid in said first mentioned circulating means when the temperature therein is above a certain predetermined value and for disposing said

fluid in said second circulating means when the temperature of said space is at or below said temperature.

13. In a refrigeration system, in combination, means forming a space whose temperature is to be regulated, a refrigeration unit adapted to cool a fluid, an internal combustion engine adapted to run continuously for substantial periods of time for driving a driven element of said unit, circulating means for said fluid adapted to bring said fluid into thermal contact with said space to extract heat therefrom, a second circulating means for said fluid substantially out of thermal contact with said space, means for forcing said medium through either of said circulating means, and means for selectively determining through which of said two circulating means said fluid is to be forced according to the temperature of said space.

14. In a refrigeration system, in combination, a space on a vehicle a whole or a part of whose interior temperature is to be regulated, a reservoir for storing brine, a refrigeration unit, an internal combustion engine adapted to run continuously for substantial periods of time to drive the compressor of said refrigeration unit, an expansion member of said unit disposed in said reservoir in thermal contact with said brine adapted to extract heat therefrom according to the rate of expansion taking place therein, a valve for controlling the rate of expansion in said member, thermostatic means in contact with said brine for controlling the action of said valve, a system of conduits connected to said reservoir and in thermal contact with said space for circulating said brine therein, a second system of conduits for circulating said brine substantially out of thermal contact with said space, a pump driven by said engine for forcing said brine through either of said systems, a valve for selectively disposing said brine in either of said systems, and thermostatic means responsive to the temperature in said space for controlling said valve to place said fluid in said first system when the temperature therein is above a predetermined value and to place said fluid in said second system when said temperature is at or below said temperature value.

15. In a refrigeration system, in combination, means forming a space whose temperature is to be regulated, means forming a circulating path for a liquid and extending into said space, a continuously acting pump for forcing said liquid through said circulating path, refrigerating means for cooling the liquid to be passed through said path, means connected with said pump and said path adapted when effective to shunt liquid away from said path, and means responsive to the temperature in said space for controlling said last mentioned means.

16. In a refrigeration system, in combina-

tion, means forming a space whose temperature is to be regulated, means forming a circulating path for a liquid and extending into said space, a continuously acting pump for forcing said liquid through said circulating path, refrigerating means for cooling the liquid to be passed through said path, means connected with said pump and said path adapted when effective to shunt liquid away from said path, means responsive to the temperature in said space for controlling said last mentioned means, and means responsive to the temperature of said liquid for controlling the refrigerating action of said refrigeration means.

17. In a refrigeration system, in combination, means forming a space whose temperature is to be regulated, means including pumping means and forming two circulating paths for a refrigerant, only one of said circulating paths being thermally related to said space, and means responsive to the temperature of said space for controlling the relative effectiveness of said two circulating paths.

18. In a refrigeration system, in combination, means forming a space whose temperature is to be regulated; a refrigerating apparatus including a continuously operated compressor for a refrigerant and means forming a path of flow for refrigerant, said last mentioned means being thermally related to said space; means for bypassing refrigerant from said path-forming means; and means responsive to the temperature of said space for controlling the relative conductivity to refrigerant of said path-forming means and said bypass means.

19. In a refrigeration system, in combination, means forming a space whose temperature is to be regulated, means including a container and forming a circulating path through said space for a liquid refrigerant contained therein, a rotary pump included in said last-mentioned means, an internal combustion engine for rotating said pump continuously for substantial periods of time, a by-pass for said pump, and valve means responsive to the temperature of said space for controlling the effectiveness of said by-pass.

20. In a refrigeration system, in combination, means forming a space whose temperature is to be regulated, a container for a refrigerant, means forming a circulating path for said refrigerant between said container and said space, refrigerating means for said container, a rotary pump in said circulating path, an internal combustion engine for driving said pump continuously for substantial periods of time, a by-pass for said pump and adapted when open to stop said pump from circulating said refrigerant in said circulating path, and valve means

responsive to the temperature of said space for controlling said by-pass.

21. In a refrigeration system, in combination, means forming a space whose temperature is to be regulated, containing means for a refrigerating brine, means for circulating said brine between said space and said containing means, said means including a rotary pump, a refrigeration unit for said containing means, an internal combustion engine adapted to drive parts of said refrigeration unit and said pump continuously for substantial periods of time, a by-pass for said pump adapted when open to reduce the effectiveness of said pump, and thermostatic means responsive to the temperature of said space for controlling the action of said by-pass.

22. In a refrigeration system, in combination, means forming a container whose temperature is to be regulated, a refrigeration unit including a compressor and an evaporating member, said evaporating member being in thermal contact with said container, means connecting the intake side of said compressor to the outlet of said evaporating member, a valve included in said last-mentioned means, and thermostatic means responsive to the temperature of the substance being refrigerated for controlling the operation of said valve.

In testimony whereof, I have signed my name to this specification this 26th day of November, 1930.
